UNITED STATES PATENT OFFICE.

H. CLAY BASCOM AND ALEXANDER WEMYSS, OF TROY, NEW YORK, ASSIGNEES TO SAID H. CLAY BASCOM.

DESIGN FOR A CYLINDER-STOVE.

SPECIFICATION forming part of Design No. 16,424, dated December 22, 1885.

Application filed November 16, 1885. Serial No. 123,049. Term of patent 7 years.

To all whom it may concern:

Be it known that we, H. CLAY BASCOM and ALEXANDER WEMYSS, citizens of the United States, residing in the city of Troy, in the county of Rensselaer and State of New York, have jointly invented and produced a new and original Design for Cylinder-Stoves, of which the following is a specification, reference being had to the accompanying engraving of a stove having said design.

This design embraces several new and distinctive parts and combinations of parts, as hereinafter specified, and shown in the aforesaid engraving.

15 One part is the shape and ornamentation of the vase A, consisting of its base *a*, body *b*, and the accumulated leaf and floral ornaments *c* on the top and opposite sides of said body, combined with the cover B, having the ornamented convex molding *d* and ornamented concave molding *e*.

The design for the front C embraces the curved surface *f*, raised quadrilateral door *g*, arched top ornamented panel *h*, and the door *i*.

25 The design for the curved side D consists of the upper ornamented panel, *j*, the oval ornamented panel *k*, and the lower ornamented panel, *l*.

The design for the stove-body embraces the 30 top E, ornamented front C, and side D, and the ornamented base-section F, as shown.

The design for the legs consists of the body portion *m*, shaped as shown, and having the circular ornament *n*, leaves *o*, and the wings 35 *p*, having the rosette ornaments *q*.

The whole design embraces the shape and ornamentation of the vase A, cover B, top E, front C, side D, base-section F, and the legs.

We claim as new—

1. In a design for a stove, the shape and 40 ornamentation of the vase A and cover B, combined as shown and described.

2. In a design for a stove, the shape and ornamentation of the front C, embracing the parts *f*, *g*, *h*, and *i*, as set forth. 45

3. In a design for a stove, the shape and ornamentation of the curved side D, embracing the parts *j*, *k*, and *l*, as set forth.

4. The design for the stove-body, consisting 50 of the cover E, front C, side D, and the base-section F, shaped and ornamented substantially as shown and described.

5. In a design for a stove, the shape and ornamentation of the legs, consisting of the parts *m* *n* *o* and *p* *q*, as shown and described. 55

6. The whole design, embracing the vase A, cover B, top E, front C, side D, base section F, and the legs, shaped and ornamented as set forth.

In testimony whereof we hereunto set our 60 hands, in the presence of two subscribing witnesses, this 13th day of November, 1885.

H. CLAY BASCOM.
ALEXANDER WEMYSS.
